PORTABLE DOUBLE DRIVE WINDING MACHINE

Filed April 14, 1939

UNITED STATES PATENT OFFICE

2,179,760

PORTABLE DOUBLE DRIVE WINDING
MACHINE

John Scoffone, New York, N. Y.

Application April 14, 1939, Serial No. 267,856

3 Claims. (Cl. 242—7)

This invention relates to a portable double drive winding machine for articles like capicollo, Geneva salami, etc.

An object of this invention is the provision of a machine for winding preserved meat articles quickly, uniformly and tightly.

Another object of this invention is to provide an automatically adjustable headstock for winding articles of different lengths.

Another object of this invention is to provide headstocks having a plurality of converging jaws with grooves of V-shaped cross-section in the engaging faces thereof, the said jaws being adapted to deeply engage the encased article being wound without penetrating the skin or casing thereof.

Another object of this invention is to provide a drive shaft having a thread substantially the entire effective length thereof, the said thread being co-extensive with the distance between the headstock jaws in fully open position, so as to utilize substantially the entire area of the machine and make it compact.

With the above and other objects in view, the invention will be hereinafter more particularly described, and the combination and arrangement of parts will be shown in the accompanying drawing and pointed out in the claims which form part of this specification.

Reference will now be had to the drawing, wherein like numerals of reference designate corresponding parts throughout the several views, in which:

Figure 1 is a plan view of the winding machine.

Figure 2 is a front elevation of the machine.

Figure 3 is a face view of one of the headstocks showing a plurality of spaced jaws of V-shaped cross-section.

Figure 4 is a side view of the cord carrier with the support for a ball of cord broken away.

In the illustrated embodiment of the invention, the numeral 10 indicates my portable double drive winding machine, comprising a base 11 having handles 12 by means of which the entire machine may be carried to different parts of a provision manufacturing establishment and mounted on any suitable table or bench.

A frame 13 has been secured to the base 11. The frame comprises upright supports 14, which are held in spaced relation by rods 15, 16 and 17 and bolts 18, threaded therein from opposite ends of the supports 14.

A headstock 20 has been rotatably mounted on a spindle 21 journalled in a bearing 22 in one of the upright supports 14. The headstock 20 has

a plurality of converging jaws 23, positioned diametrically of the headstock. Each of the jaws 23 has a groove of V-shaped cross-section, best shown in Figure 3, so as to form V-shaped engaging grooves adapted to grip an object placed between the headstocks at a plurality of linearly and diametrically disposed portions, especially that of an oval shaped end of an article being wound or bound.

A duplicate headstock 20 has been rotatably mounted on a spindle 24 journalled in a bearing 25 at the upper end of a bracket 26. The bracket 26 is slidably mounted on the rods 15 and 16. The spindle 24 is also slidably mounted in a bearing 22 in one of the upright supports 14. A coil spring 27 constantly forces the slideable headstock in direction of the non-slideable headstock. The V-shaped cross-sections of the grooves of the jaws 23 serve to substantially deeply engage the yielding exterior portions of the article being wound without penetrating the skin or casing thereof.

The headstock spindles 21 and 24 have gears 30 secured thereto. A drive-shaft 31 has been rotatably mounted in bearings in the upright supports 14. Gears 32 have been secured thereto at opposite ends. An electric motor 33 has been fastened to the base 11 and through suitable pulleys 34, 35, imparts rotation to the drive-shaft 31. Gears 36 rotatably mounted in bearings in the upright supports 14 have been positioned in meshed engagement with the gears 30 and 32 and when the motor is in operation cause both headstocks to be positively rotated in the same direction.

A handwheel 37 secured to the spindle 38 of one of the gears 36 serves for manually rotating the headstocks or for giving the headstocks a partial rotation at the finish of the winding operation when the motor is shut off and the winding cord has not reached the extreme end of the article being wound.

The winding of the article of provision is preferably accomplished with a cord. The cord feeder comprises a lead screw 40 in the form of a square thread 41 cut on the drive-shaft 31. The thread 41 extends substantially the entire effective length of the winding machine, that is, the length of the thread is co-extensive with the distance between the headstock jaws in fully extended or fully open position.

The cord carrier 42 comprises an elongated tubular portion 43 in slidable engagement with the rod 17. The cord carrier comprises an arcuate bar 44 having a semicircular and internally 55

threaded body 45 adapted for engagement with the thread 41. A ball of cord 46 has been mounted on a support 47 having an upper cord threading portion 48. The bar 44 has two spring-pressed threading members 49, 49, and an intermediate free threading eye-shaped guide member 50 and an aperture 51. The cord 46 is threaded through guide member 50 and through the tensioning members 49, 49, as shown in Figure 4, for guiding and tensioning the cord. The member 50 serves to prevent knotting. The free delivery of an unknotted cord in position for winding is thereby assured.

As best shown in Figure 1, the thread 41 terminates short of the hub of the pulley 35, leaving a reduced shaft portion 52 on which the internally threaded body 45 of the cord carrier 42 is brought to rest. This reduced or undercut shaft portion 52 is of a diameter corresponding to the bottom of the thread 41. When the cord carrier 42 is fed by the thread in direction of the arrow, it assumes a stationary position when it reaches the shaft portion 52. This automatic arresting of the feed-motion of the cord carrier provides a safety feature in the operation of the machine. It is to be noted that an elongated keyway 53 has been cut in the spindle 24. The keyway is in engagement with a key (not shown) in the gear 36. The key and keyway make the spindle 34 rotatable in all slidable positions.

It is to be noted that while I have shown a semi-circular and internally threaded body 45 for detachable engagement with the screw thread 41, that I may employ a split threaded nut (not shown) in engagement with the screw thread and to detach both nut members from the thread, as is well known.

In accordance with the patent statutes I have described and illustrated the preferred embodiment of my invention, but it will be understood that various changes and modifications can be made therein without departing from the spirit of the invention as defined by the appended claims.

45 I claim:

1. In a portable double drive winding machine for food articles having a penetrable skin of the class described, a frame, a headstock having converging jaws with grooves of V-shaped cross-section in the engaging faces thereof, said headstock being rotatably mounted on a spindle and being positively driven, a slidable headstock having converging jaws with grooves of V-shaped cross-section in the engaging faces thereof and being mounted on a spindle in alignment with said first headstock, each of said headstocks being adapted to substantially deeply engage the article being wound without penetrating the skin thereof, a drive-shaft having gears at opposite ends, said headstock spindles having gears thereon, intermediate gears mounted on said frame and meshing with said drive shaft gears and with said spindle gears and causing said headstocks to positively rotate in the same direction, said slid-
60 able headstock being spring-urged in direction of said first headstock, whereby said headstocks are adapted to resiliently grip and press from opposite ends articles of varied lengths placed therebetween for winding.

resiliently grip and press from opposite ends an article placed therebetween for winding.

2. In a portable double drive winding machine for food articles having a penetrable skin of the class described, a frame, a headstock having converging jaws with grooves of V-shaped cross-section in the engaging faces thereof, said headstock being rotatably mounted on a spindle and being positively driven, a slidable headstock having converging jaws with grooves of V-shaped cross-section in the engaging faces thereof and being mounted on a spindle in alignment with said first headstock, each of said headstocks being adapted to substantially deeply engage the article being wound without penetrating the skin thereof, a drive-shaft having gears at opposite ends, said headstock spindles having gears thereon, intermediate gears mounted on said frame and meshing with said drive shaft gears and with said spindle gears and causing said headstocks to positively rotate in the same direction, said slid-
10 able headstock being spring-urged in direction of said first headstock, said slidable headstock spindle having a keyway in engagement with a key in the gear mounted thereon and being rotatable in all its slidable positions, whereby said headstocks are adapted to resiliently grip and press from opposite ends articles of varied lengths placed therebetween for winding.

3. In a portable double drive winding machine for food articles having a penetrable skin of the class described, a frame, a headstock having converging jaws with grooves of V-shaped cross-section in the engaging faces thereof, said headstock being rotatably mounted on a spindle and being positively driven, a slidable headstock having converging jaws with grooves of V-shaped cross-section in the engaging faces thereof and being mounted on a spindle in alignment with said first headstock, each of said headstocks being adapted to substantially deeply engage the article being wound without penetrating the skin thereof, a drive-shaft having gears at opposite ends, said headstock spindles having gears thereon, intermediate gears mounted on said frame and meshing with said drive shaft gears and with said spindle gears and causing said headstock to positively rotate in the same direction, said drive-shaft being threaded substantially its entire length, a guide bar fixed in said frame parallel to said drive-shaft, a cord carrier in slidable engagement with said guide bar and having means for engaging with said thread, said thread having an undercut portion to permit disengagement of said cord carrier from said drive-shaft thread at the end of travel, said slidable headstock being spring-urged in direction of said first headstock, said slidable headstock spindle having a keyway in engagement with a key in the gear mounted thereon and being rotatable in all its slidable positions, whereby said headstocks are adapted to resiliently grip and press from opposite ends articles of varied lengths placed therebetween for winding.

JOHN SCOFFONE.
